(57) **CLAIM**

The ornamental design for a pipe spacer, as shown and described.

DESCRIPTION

FIG. 1 is a top perspective view of a pipe spacer according to an embodiment of the application.

FIG. 2 is a bottom perspective view of the pipe spacer shown in FIG. 1.

FIG. 3 is a front view of the pipe spacer shown in FIG. 1.

FIG. 4 is a rear view of the pipe spacer shown in FIG. 1.

FIG. 5 is a top view of the pipe spacer shown in FIG. 1.

FIG. 6 is a bottom view of the pipe spacer shown in FIG. 1.

FIG. 7 is a first side view of the pipe spacer shown in FIG. 1; and,

FIG. 8 is a second side view of the pipe spacer shown in FIG. 1.

The elements shown in broken lines are included for the purpose of illustrating environment and form no part of the claimed design.

1 Claim, 8 Drawing Sheets
